(57) **CLAIM**

The ornamental design for a flower power shaped night light, as shown and described.

DESCRIPTION

A portion of the disclosure of this patent document contains material, which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a front perspective view of translucent acrylic flower power shaped night light with the core shape in the form of a flower, the electrical prongs are shown in broken lines, according to my design;

FIG. 2 is a rear perspective view thereof;

FIG. 3 is a front view thereof;

FIG. 4 is a rear view thereof;

FIG. 5 is a left side view thereof; right side view is a mirror thereof; and,

FIG. 6 is a top and bottom view thereof.

The broken line showing of flower power shaped night light is included for the purpose of illustrating portions of the article and forms no part of the claimed design.
